CONCRETE PIPE MAKING APPARATUS

Peter M. Matich, San Jose, Calif.

Application May 11, 1953, Serial No. 353,971

5 Claims. (Cl. 25—30)

1

The present invention relates to an improvement in concrete pipe making machines, and pertains more particularly to a platform and support structure for the rotatable form in which pipes of this character are made.

It is common practice in the manufacture of concrete pipe to employ a rotatable cylindrical shell which forms the outer portion of the pipe mold around a stationary core. A steel mesh reinforcing element usually is inserted in the space between the core and the rotatable shell, especially in making the larger diameters of pipe. Concrete is poured into the space between the core and the shell during rotation of the shell, and at the same time the concrete is tamped down as it is poured into the mold space between the shell and the core. This operation forms extremely strong concrete pipe.

In the past, difficulty has been experienced in rotating the shell when molding the larger sizes of pipe, since a great amount of friction is caused by the rotation of the bottom of the shell on the steel plate platform upon which it revolves, and also between the stationary core and the inner face of the rotating concrete pipe as it is being formed.

Various attempts have been made in the past to provide suitable rolling support for the rotatable shell, but such supports soon fill up or become fouled with concrete which spills over the side of the form and eventually are worse than the smooth metal base plate, which at least is easily cleaned.

The present invention contemplates the provision of an improved concrete pipe making machine. Another object of the invention is to support the rotatable shell of a concrete pipe making machine on roller supports which are easily adjusted to provide proper support for the shell bottom and which may be withdrawn into the base plate and shielded from the entrance of cement or sand into their rotative portions, the shielding means being flush with the base plate.

These and other objects and advantages of the invention will be apparent from the following description and the accompanying drawings, wherein

Fig. 1 is a side elevational view of a concrete pipe making machine embodying the present invention, portions being broken away and a steel plate floor structure being shown sectionally.

Fig. 2 is a horizontal sectional view in reduced scale taken along line 2—2 of Fig. 1.

Fig. 3 is an enlarged fragmentary, vertical sectional view taken along line 3—3 of Fig. 1.

Fig. 4 is a fragmentary elevational view looking in the direction of the arrows 4—4 in Fig. 1, portions being broken away.

Fig. 5 is a reduced sectional view taken along line 5—5 of Fig. 1.

Fig. 6 is a longitudinal, sectional view on the same scale as Fig. 2, of a section of concrete pipe made on the machine shown in Figs. 1 to 5 inclusive, the reinforcing steel ordinarily provided in such pipes being omitted for the purpose of simplifying the drawings.

Referring to the drawings in detail, a concrete pipe making machine A (Fig. 1) embodying the present invention, comprises a stationary core 15 member B and a cylindrical shell C mounted to rotate with a circular base plate 9 upon which the shell C is mounted. Concrete is poured into the space between the core B and the shell C and is rammed solidly therein and finished off on the ends in a manner to be described later herein. The machine A is mounted over a customary pit 10 with steel floor plates 11 and 11a reinforced by a transverse I-beam 12.

A pair of laterally spaced vertical standards 13—13 (Figs. 2 and 4) of channel cross sectional shape are mounted on the base plate 11 to overlie the I-beam 12. A transversely extending box beam 14 is mounted for vertical slidable adjustment between the standards 13—13. The ends 30 of the transverse beam are notched out as at 15, 15 to receive the upright standards 13, 13 therein. The transverse beam 14 is secured in desired vertically adjusted position on the standards 13, 13 by a pair of studs 17, 17 (Figs. 1 and 4). Each stud 17 has a threaded portion 18 adjacent the head 18a thereof for screwing into a selected one of a plurality of threaded holes 20 provided at spaced intervals along the standards 13, 13.

The inner end portions 21 of the studs 17 are of reduced diameter and are unthreaded to extend into the ends of the box beam 14 (Fig. 4) and secure it at a desired adjusted height.

For raising and lowering the box beam 14 and a tamping head assembly D mounted thereon, a hydraulic cylinder 22 with extensible piston rod 23 is mounted on the base plate 11 over the reinforcing I-beam 12. The cylinder 22 is secured to the base plates 11 and 11a and the piston rod 23 to the transverse beam 14 by screws 24, 24 (Figs. 1 and 4). Usual hydraulic controls (not shown) are provided to actuate the piston rod 23 within the cylinder 22 to elevate or lower the box beam 14 and the tamping head assembly D mounted thereon in a conventional manner.

The tamping head D comprises a large diam-

eter cylindrical drum 27 mounted on a friction reducing bearing 28 on the box beam 14 over the piston rod 23. The upper end of the drum 27 is pivotally mounted co-axially with the lower bearing 28 on a second friction reducing bearing 28a secured to the underside of an upper transverse box section beam 29. The upper beam 29 is generally similar to the lower box beam 14, and is mounted in a similar manner for vertical slidable movement on the standards 13, 13.

The tamping head structure D comprises a motor support bracket 31 welded to extend laterally from the lower end of the cylindrical drum 27, and a suitable electric motor 32 is mounted on the bracket. The motor 32 has driving connection through grooved pulleys 33 and 34 and V-belts 35, 35 with a shaft 36 journaled in bearings 37, 37 mounted one in each end of a casing 38, which extends transversely through the drum 27. The opposite end of the shaft 36 from that having the pulley 34 thereon has a disk 39 mounted coaxially thereon with an eccentric pin 40 mounted therein to extend outwardly therefrom.

A diagonal bracing member 41 is welded to extend from the upper end of the drum 27 to the top of the casing 38 substantially midway between the drum 27 and the outer or right hand end of the casing as shown in Fig. 1.

The upper end of a connecting rod 42 is journaled on the eccentric pin 40, and its lower end is journaled on a pin 43 secured to extend laterally from a pneumatic clamping member 44. This pneumatic clamping member is of a conventional type for gripping a wooden tamping rod 45 and is slidably mounted to reciprocate on a pair of vertical rods 46, only one of which is visible in Fig. 1. The rods 46 are secured to extend vertically between a pair of horizontally extending arms 47 and 48 secured to the drum 27. A vertical brace bar 49 connects the centers of the arms 47 and 48.

The pneumatic clamping member 44 has usual clamping jaws (not shown) which are pneumatically actuated to grip the tamping bar 45. The tamping bar is of hardwood with its lower end somewhat rounded to ram up the concrete as it is poured into the space between the stationary core B and the rotating shell C.

It is customary in making concrete pipe of this type to employ a cylindrical steel mesh or rod reinforcement which fits into the space between the core B and the shell C and is embedded in the pipe when formed. However, since this type of reinforcement is well known, it is omitted from the present case for the sake of simplicity.

The rotary shell C comprises a customary pair of semi-cylindrical shell half members 50 and 51 secured together by encircling bands 52, the ends of which are drawn together by screws 53 to secure the two semi-cylindrical half members 50 and 51 firmly together. The lower ends of the cylindrical shell half members 50 and 51 fit into a circular recess provided therefore in the circular base plate 9 which at its center has driving connection with a square shaft 55. The lower end portion 55a of the shaft 55 is round and is journaled in a bearing 57 secured to the under side of the base plate 11. The upper end (not shown) of the shaft 55 also is round and is similarly journaled in an upper bearing, not shown.

The shaft 55 is driven by bevel gears 59 and 60 from a shaft 61 journaled in a bearing 61a 75

secured to the under side of the base plate 11. The opposite end of the shaft 61 is driven by suitable transmission gearing (not shown) mounted in a conventional gear housing 62. The gear housing 62 is mounted on a beam 63 provided therefor in the pit 10 over which the machine A is mounted.

The gearing in the gear housing 62 is driven by a shaft 64 from a variable speed transmission gearing, not shown, similar to an ordinary automobile truck type transmission mounted in a housing 65. Selection of the gears in the housing 65 is made by a usual gear shift lever 65a. The transmission gearing in turn is driven by shaft 67 which is connected to a suitable prime mover (not shown) such as a conventional electric motor of suitable horsepower.

A strike-off plate 70 is mounted on the upper end of the core B just ahead of a concrete pouring spout 71, so that when the cylindrical space between the core B and the shell C becomes filled, the plate 70 will strike off excess concrete and will trowel the upper end of the concrete pipe section formed in the space between the core B and shell C to the cross sectional shape shown at the upper end of the pipe E of Fig. 6.

The lower end of the pipe is molded by a usual molding ring 72 (Fig. 1) inserted in the bottom of the space between the core B and shell C to a shape complementary to that of the upper end of the pipe so that successive sections of pipe of the same diameter will have interfitted relation when laid in coaxial juxtaposition to each other.

For making pipe sections of different diameters, the core B, shell C, bottom forming ring 72, and rotary base plate 9 are removed and others of desired diameters are substituted therefor. Customarily, forms are provided to manufacture pipe varying in diameter from approximately one foot to six feet.

In making the smaller diameters of pipe, the power provided to rotate the base plate 9 and shell C, together with the mass of concrete being built up in the space between the stationary core B and the rotating shell C, is relatively small. Therefore, in the making of these smaller sizes of pipe it is not necessary to provide friction reducing means between the rotary base plate 9 and the floor plate 11. However, as the diameter of the pipe being manufactured increases, the frictional drag caused by the rubbing of the base plate 9 on the floor plate 11 when no friction reducing means is provided becomes tremendous. The result is that the machines frequently break down or stall, requiring considerable periods of shutdown with resultant loss of capacity during the shutdown time of the machines.

The friction reducing means provided by the present invention comprises a plurality of roller support brackets 75, one of which is provided beneath each of a plurality of holes 77 in the floor plate 11.

A roller 78 is journaled on a shaft 78a in each of these brackets with its axis of rotation disposed along a radius from the center of rotation of the square, upright shaft 55. The sides surrounding each hole 77 are sloped inwardly toward their bottom edges, and a closure plate 79 is provided for fitting into each of the holes 77 to seal it off when the roller therefore is retracted to an inactive position below the floor plate 11.

Each roller shaft 78a is mounted (Fig. 3) on

a yoke 80 which in turn is slidably mounted in slots 81 provided in the sides of each bracket 75. An adjusting screw 82 is threaded through the lower end of each of the brackets 75 to bear against the center of its associated roller support yoke 80 and is secured in vertically adjusted position by means of a lock nut 83. It is not necessary to provide rollers 78 for the smaller diameters of pipe to be manufactured, and in the illustrations of Fig. 2 it may be assumed that the innermost of the rollers are for supporting the rotary base plate 9 for making a pipe section approximately three feet in diameter.

The three sets of rollers 78a, 78b, and 78c, shown in Fig. 2, may be used selectively to support the base plates 9 and shells C for the manufacture of the larger diameters of pipe up to, for example, six feet or even more in diameter.

For making the smaller diameters of pipe for which it is unnecessary to use the rollers 78, the adjusting screws 82 are screwed downwardly to lower the rollers 78 below the level of the floor plate 11. The closure plates 79 then are put into the roller openings 77 above the lowered rollers to keep the lowered rollers and their supporting mechanism free of cement.

When it is desired to use a base plate 9 and shell C for manufacturing a large diameter of pipe as shown in Fig. 1, the outermost set of rollers 78 which will fit beneath the selected base plate 9 are then elevated, after removing the closure plates 79 thereover, by turning the screws 82 to elevate the yokes 80 and their supported rollers 78 to a height which brings their tops into supporting relation with the base plate 9 as illustrated in Figs. 1 and 3. The rollers 78 maintain the base plate 9 clear of the floor plate 11 by a distance which will prevent substantial frictional engagement with any concrete which may be spilled on the floor plate 11 and pass beneath the rotary base plate 9.

The invention provides a free rolling support for the base plate 9 and the shell C supported thereon for even the largest sizes of pipe manufactured. The simple and positive elevating means and closure arrangements withstand indefinitely the severe usage to which they are put, and the closure plates may be easily freed from their seats even after a prolonged period in which they are subjected to accumulations of concrete and moisture.

While I have illustrated and described a preferred embodiment of the present invention, it will be understood however, that various changes and modifications may be made in the details thereof without departing from the spirit and scope of the invention as set forth in the appended claims.

Having thus described the invention, what I claim as new and desire to protect by Letters Patent is defined in the following claims.

I claim:

1. In a concrete pipe making machine of the type having a tamping head mounted for vertical adjustment over a floor plate, a stationary cylindrical core mounted in axially upright position adjacent the tamping head, a rotary base plate mounted in superposed relation over the floor plate and coaxially with the core, and a cylindrical shell mounted coaxially with and in driven relation with the base plate, and spaced from said core to provide a space for molding a concrete pipe section; said floor plate having a plurality of openings therein arranged symmetrically about the axis of rotation of the base plate, a bracket mounted beneath the floor plate

to span each roller opening therein, a roller support mounted in each of said brackets for vertical guided movement therein, a roller journaled in each roller support, adjusting means mounted 5 to bear against each roller support selectively to elevate the roller into rolling supporting relation with a base plate extending thereover, and to lower the roller below the support plate, and a closure plate for each of the openings to seal 10 the opening against the entrance of concrete therein.

2. In a concrete pipe making machine of the type having a tamping head mounted for vertical adjustment, a stationary cylindrical core 15 mounted in axially upright position, a rotary base plate mounted in superposed relation over the floor plate and coaxially with the core, and a cylindrical shell mounted coaxially with and in driven relation with the base plate, and spaced from said core to provide a space for molding a concrete pipe section; said floor plate having a plurality of openings therein arranged symmetrically about the axis of rotation of the base plate, a bracket mounted beneath the floor plate 20 to span each roller opening therein, said bracket having a vertical guideway therein, a yoke mounted in each of said brackets for vertical guided movement in the guideway therein, a roller journaled in each yoke, an adjusting screw mounted in each bracket to bear against the underside of the yoke therein, selectively to elevate the roller into rolling supporting relation with a base plate extending thereover, and to lower the roller below the support plate, means 25 for securing the screw and its supported parts in adjusted position, and a closure plate for each of the openings to seal the opening against the entrance of concrete therein.

3. In a concrete pipe making machine of the type having a rotary pipe mold and tamping means adjustably mounted over a floor plate, said floor plate having a plurality of openings 30 therein arranged symmetrically at a plurality of predetermined distances radially from the axis of rotation of the mold, a roller mounting bracket mounted beneath the floor plate adjacent each roller opening therein, a roller support adjustably mounted in each of said brackets, a roller journaled in each roller support, and adjusting means mounted to bear against each roller support selectively to elevate the roller into rolling, supporting relation with the mold, and to lower the roller below the support plate, means 35 for securing the screw and its supported parts in adjusted position, and a closure plate for each of the openings to seal the opening against the entrance of concrete therein.

4. In a concrete pipe making machine of the type having a stationary cylindrical core member, a rotary shell surrounding said core member and spaced outwardly therefrom to provide a space between the core member and the shell for molding a concrete pipe section therein, a vertically adjustable tamping head assembly, 40 having a tamping element thereof positioned to extend into the space between the core and the shell, a rotary base plate with its axis of rotation co-incident with the shell axis, and a floor plate mounted over a pit for supporting said base plate; said floor plate having a plurality of openings therein disposed in symmetrical arrangement about the axis of rotation of the base plate and spaced at selected intervals therefrom, a roller mounted in each of said openings with its axis disposed along a radius from the axis of rotation of the base plate, each of the rollers being 45

vertically adjustable from an elevated position wherein its periphery projects above the floor plate into rolling contact with said rotary base plate to a position below the floor plate, and a removable closure member for flush mounting with the floor plate in each of the roller openings therein.

5. In a concrete pipe making machine of the type having a stationary cylindrical core member, a rotary shell surrounding said core member and spaced outwardly therefrom to provide a space between the core member and the shell for molding a concrete pipe section therein, a vertically adjustable tamping head assembly having a tamping element thereof positioned to extend into the space between the core and the shell, a rotary base plate with its axis of rotation co-incident with the shell axis, and a floor plate mounted over a pit for supporting said base plate; said floor plate having a plurality of open-

ings therein disposed in symmetrical arrangement about the axis of rotation of the base plate and spaced at selected intervals therefrom, a roller mounted in each of said openings with its axis disposed along a radius from the axis of rotation of the base plate, each of the rollers being vertically adjustable from an elevated position wherein their peripheries project above the floor plate into rolling contact with said rotary base plate to a position below the floor plate, a removable closure member for flush mounting with the floor plate in each of the roller openings therein, and roller actuating means mounted beneath the floor plate for forcing a roller upwardly to elevate its closure member clear of the floor plate and to bring the roller into rolling supporting relation with the base plate.
